UNITED STATES PATENT OFFICE.

HERMAN J. JAEGER, OF WEEHAWKEN, NEW JERSEY, ASSIGNOR TO H. J. JAEGER COMPANY, OF HOBOKEN, NEW JERSEY, A CORPORATION OF NEW JERSEY.

INCANDESCENT LAMP WITH CONCENTRATED METALLIC FILAMENTS.

1,197,207.

Specification of Letters Patent. Patented Sept. 5, 1916.

Application filed April 10, 1915. Serial No. 20,415.

To all whom it may concern:

Be it known that I, HERMAN J. JAEGER, a citizen of the United States of America, and a resident of Weehawken, county of Hudson, State of New Jersey, have invented certain new and useful Improvements in Incandescent Lamps with Concentrated Metallic Filaments, of which the following is a specification.

10 This invention has reference to improvements in metallic filament lamps.

It pertains particularly to lamps provided with so called concentrated metallic filaments as the incandescing body and has for 15 its special object to produce a lamp of this kind which is provided with two independent sections of a filament of which each section may be burned separately or both sections may be burned simultaneously. Thus, 20 the present lamp actually contains two lamps in one and constitutes a lamp of say, standard candle power or twice the candle power of such standard lamp.

Assuming that each section or half of the 25 filament burns at 110 volts and consumes a certain number of watts of some standard lamp, then such section or half of the filament represents in itself a standard lamp. When burned out, the second section or half 30 of the filament of like voltage and wattage may be burned independently, whereby the life of the lamp is double or, if desired, both sections may be burned simultaneously for the purpose of obtaining double candle power.

These desirable objects have been primarily attained by the use of three leads with such accessory parts as are required for rendering it possible to bring one section or 40 half of the filament into the circuit, or the other half or both simultaneously.

In order to render the invention entirely clear, reference is had to the accompanying drawing, in which:

45 Figure 1 represents in elevation, an incandescent electric lamp with concentrated metallic filaments embodying in desirable form, the present improvements. Fig. 2 is a bottom plan view relative to Fig. 1. Fig. 50 3 illustrates the upper portion of a suspended lamp partly in section showing the leads connected so as to have both filament sections in the circuit. Fig. 4 is a similar

section showing the leads so connected that but one section or half of the filament is in 55 the circuit.

Similar characters of reference denote like parts in all the figures.

In the drawing, *a* represents the lamp globe, *b* is the neck, and *c* the inner stem 60 or support. There are three leads passing through the solid portion *c*¹ of the support. The leads are fused therein with the short platinum wires in the usual manner. From the stem or support the three leads extend 65 inwardly into the globe and form partly the supports for the incandescing filament. A wire *d* is fused centrally into the support or stem and isolated therefrom. The wire *d* carries a glass rim *e* fused to its inner end. 70 The glass rim carries a plurality of filament supports which are fused therein. Six of these supports are shown in Fig. 1. Two of these supports *f*, *g* are rather heavy and carry each a fine wire support *f*¹, *g*¹ which 75 extends as far as the leads. At the ends of these supports, small loops are formed. The four other filament supports *h*, *i*, *j*, *k* are relatively short, they consist of wires only and also form each a loop at the end. 80

As herein mentioned there are three leads, one heavy lead *l* passes through the stem on one side, while the two leads *m*, *n*, are close together and pass through the stem at the opposite side. There are two independent 85 filaments *o*, *p* in this lamp, but two of their ends are attached to the principal lead *l*, while the opposite end of one filament section or filament half is attached to the lead *m* and the second end of the second filament 90 half or section to the lead *n*. Thus, both filaments form a single uninterrupted filament which however, is open there being a space between the leads *m*, *n* which is free from any filament portion. In order to concentrate the light, the filament is bent up and down passing alternately and successively through the short and long supports. 95

To render it possible to light each filament section or half independently or both together simultaneously means are provided within the socket for attaining this purpose. 100

The principal lead *l* is always connected to the base *q* at the point *q*¹ in the usual manner. The two other leads *m*, *n* which are 105 close together and opposite the principal

lead are connected within the base so that one alone, m may be connected in the circuit for illuminating one section or half of the filament or both wires may be connected simultaneously for illuminating both sections or halves of the filament. This may be accomplished in various ways. In Figs. 3 and 4, one example of construction is shown in which the lead m is in electric connection with a sleeve r . This sleeve is threaded on the inside and acts as a nut for the screw s which thus, is electrically connected with the lead m . Assuming that the screw s is in the position indicated in Fig. 4, then an air gap exists between the screw and the other parts within the base g . This air gap or air space acts as an insulator and when the lamp is applied to a socket, then electric connection is made with the principal lead and with the screw and thereby with the lead m . Accordingly the filament section o alone is rendered incandescent. If it is desired to light both filament sections o and p then the lamp is removed from the socket and the screw s screwed down upon the adjoining parts within the base. The metal washer s^1 on the screw s now contacts with the metal washer u to which the lead n is connected both being insulated by a rubber washer v . Now the lamp is applied to the socket and as all the three leads are in the circuit both filament sections are lighted simultaneously. Should one filament section or half burn out, the other one will burn independently. If the filament half o burns out the screw s is screwed down so as to place the filament section p into the circuit, and if the filament section p is burnt out, then the screw s makes connection no matter whether it is in the position shown in Fig. 4 or Fig. 3.

I claim as my invention:

1. An incandescent lamp with concentrated metallic filaments comprising a globe with a stem, three leads passing through said stem, a filament support fused centrally therein, a glass rim at its free end, two long supports and four short supports fused into said rim, and two independent filaments connected with one end each to one lead and with the other end each to one of the two other leads and passing alternately through the short and long supports, and means in connection with the leads to render one filament incandescent or both simultaneously. 55

2. An incandescent electric lamp comprising a stem, a filament support fused centrally therein, a glass rim at its free end, a few long supports, and a double number of short supports fused into the said rim, two independent concentrated metallic filaments passing alternately from the short to the long supports, and means in connection with the filaments to render one incandescent or both simultaneously. 60

3. An incandescent electric lamp comprising a stem, a filament support fused centrally therein, a glass rim at its free end, two long supports on said rim, four short wire supports fused into said rim, two independent concentrated metallic filaments passing alternately from the short to the long supports, and means in connection with the said filaments to render one filament incandescent or both simultaneously. 70

Signed at New York, N. Y., this 9th day of April, 1915.

HERMAN J. JAEGER.
